WILLY HEERTSCH, OF ERFURT, GERMANY

DIRECTION INDICATOR

Application filed October 24, 1930, Serial No. 490,870, and in Germany September 25, 1930.

This invention relates to a direction indicator, especially for motor cycles.

Direction indicators for motor cycles are known, which are so constructed that an arrow indicator casing is fastened beside each handle on the inner side of the handle bar. When operated, the arrow indicator swings outwards so that it stands horizontally at right angles to the arrow indicator casing. Direction indicators of this type are open to the objection, that the indicator is covered by the hand on the handle or by the arm so that in operative position it cannot be seen from vehicles following up. As a signal visible to following vehicles is necessary for the absolute safety of traffic, the indicators of this type do not fulfill their purpose.

The direction indicator according to the invention is absolutely visible in operative position from the front as also from the rear. It projects in operative position, as is the fundamental condition for a motor cycle direction indicator, beyond the outermost lateral points of the vehicle. These points are on each side the outermost ends of the handles on the handle bar. The direction indicator according to the invention is so constructed, that the arrow casing is fastened crane-like on the inner side close to the handles in horizontal position extending outwardly and approximately flush with the outer ends of the handles. The operation of a lever arranged directly on the arrow casing and to be easily reached with a finger of the hand on the handle in question, without it being necessary to remove the hand from the handle, causes the direction indicator arrow mounted on the outer end of the arrow casing to swing out upwardly from the casing through an arc of 180° over the handle of the handle bar so that it is in the opposite position as in the inoperative position. As the arrow can in no way be screened in this position by the hand or the arm, it is clearly visible from the rear, so that the indicator in this novel construction entirely fulfills the requirements.

By a sudden lever pressure the indicator is again returned into the arrow casing. During its swinging out movement an electric

contact is closed, so that in the arrow, the walls of which are transparent in known manner, a lamp is illuminated and a perfect working of the indicator is ensured in the dark. As the arrow casing is fastened crane-like only on the inner ends of the handles, a hindrance of the hands is absolutely impossible.

An embodiment of the invention is illustrated by way of example in the accompanying drawings in which:

Fig. 1 shows the direction indicator seen from the inner side, partly in section, on the handle bar on the left side in inoperative position.

Fig. 2 is a top plan view in longitudinal section of Fig. 1.

Fig. 3 shows the direction indicator in rear end view.

Fig. 4 shows the direction indicator arrow in extended position in longitudinal section.

Fig. 5 shows in perspective view the direction indicator in operative position on the handle bar.

An indicator arrow *e* is oscillatably mounted in an arrow casing *c*. The oscillation of the arrow is effected by a rack *f*, which engages with bolts *g*, arranged concentrically around an axis *d* of the arrow *e*. On the rack *f*, which is accommodated in the arrow casing *c*, so a bolt *i* is arranged, which projects outwardly through a slot *e*. The bolt *i* engages a lever *k* mounted on a pivot *v* (Fig. 1). If, when the arrow is not extended, the lever *k* is moved towards the right, the rack *f* participates in this movement so that the bolts *g* engage successively in the tooth gaps *h* of the rack *f*. The arrow *e* is thus swung outwardly so that it projects towards the side.

The lever *k* is held in its two extreme positions by a spiral spring *m* fixed at one end on the bolt *i* and at the other end on the arrow casing *c*. The fastening of the spring *m* on the bolt *i* prevents at the same time the lever *k* from jumping off the bolt *i*. In order to cushion the arrow *e*, when it is swung inwards, a pad of rubber or similar material is arranged in the casing *c*. In order to cushion the arrow when swinging out, a pad *w* is provided in the casing *c* (Fig. 1). For the

purpose of illuminating a lamp *s* in the arrow provided with transparent walls *u*, when this arrow is swung outwards, and to keep said lamp burning when the arrow is in swung out position, a contact is closed in this position between a bolt *q* arranged insulated in the arrow *e* and connected to one pole of the lamp *s* by a wire *r* and a metal blade spring *p* secured on the bottom of the arrow casing by an insulated bolt *o*. The contact spring *p* is connected to one pole of a battery by means of a cable *n*, whereas the connection with the other pole and the lamp *s* is effected in known manner through the mass. In order for the lamp *s* to be resiliently mounted in the arrow *e*, it is secured by means of a rivet on the arrow frame with the aid of a bow *t*. If it is desired to change a lamp *s*, which has become defective, the wall of the arrow in question is removed by unscrewing the nuts *y*, so that the wall can be lifted out and its point *x* easily pulled out of the clip of the counter wall. The arrow casing *c* is secured to the handle bar by a metal rod *z* arranged vertically thereon engaging with a clamping screw, which is arranged on the clip *b* surrounding the handle bar. By this arrangement it is possible, when fitting the indicator, to easily bring same into the proper position according to the shape of the handle bar.

Owing to the fact that the indicator arrow in the inoperative position as also in operative position lies horizontally, it is supported in both instances by the arrow casing, so that a wearing of the supporting parts through vibration and the like is absolutely avoided.

I claim:

1. A direction indicator for motor cycles, comprising in combination, a crane-like horizontally extending arrow casing, open at the top, and having a slot in its outer wall, an arrow within said casing, an axis for said arrow, said axis being fixed to said casing bolts arranged concentrically around said axis, on said arrow, a rack within said casing, said rack engaging said bolts and effecting the oscillation of said arrow, a bolt on said connecting rod projecting through the slot in the wall of said casing, a pivot on the outside of said casing, a control lever mounted on said engaging said last named bolt, and a spiral spring fastened at one end to said bolt and at the other end to said casing adapted to secure said control lever in both controlling positions.

2. A direction indicator for motor cycles as specified in claim 1, comprising in combination with the arrow casing and the arrow, a rod arranged perpendicularly to said casing at the opposite end to that at which said arrow is oscillatably mounted, a clip adapted to surround the handle bar of the motor cycle and fix this indicator in position through the intermediary of said rod.

3. A direction indicator as specified in

claim 1, comprising in combination with the casing and the indicating arrow, a clip on the point of said arrow, and a screw on the head of said arrow, said arrow adapted to be taken to pieces on said screw being removed and said clip being disengaged.

In testimony whereof I affix my signature
WILLY HEERTSCH.
